UNITED STATES PATENT OFFICE.

ETHEL M. RYAN, OF HAWKINSVILLE, GEORGIA.

COMBINED GRATE-FENDER AND ASH-PAN.

1,189,389.

Specification of Letters Patent.

Patented July 4, 1916.

Application filed April 21, 1915. Serial No. 22,927.

To all whom it may concern:

Be it known that I, ETHEL M. RYAN, a citizen of the United States, residing at Hawkinsville, in the county of Pulaski and State of Georgia, have invented certain new and useful Improvements in a Combined Grate-Fender and Ash-Pan, of which the following is a specification.

My invention relates to certain new and useful improvements in grate fenders, and more particularly to a combined fender and ash pan, primarily designed to be used in connection with open grates to receive the ashes ejected from the bottom, and to catch and collect the live coals, sparks and other particles falling from the unprotected side thereof.

The main object of my invention is to provide a device of the foregoing nature where- 20 in the fender structure is preferably held in pivotal relation with the body in order that it may be quickly operated to deposit its contents in the ash pan.

Another object is to arrange the fender structure in such manner whereby it serves a dual function, namely to catch the live coals and sparks falling from the unprotected side of the grate and, as a cover to protect that portion of the ash pan project- 30 ing beyond the front edge of the grate.

Other servient objects will become apparent during the continuance of the following description.

The above and other objects which will be- 35 come apparent are accomplished by such means as are shown in their preferred form in the accompanying drawing, described in the following specification and then more specifically pointed out in the appended 40 claims.

In the accompanying drawings wherein is illustrated the preferred embodiment of my invention and like numerals designate like parts throughout the several views; Figure 1 is a perspective view of my invention. Fig. 2 is a plan view thereof. Fig. 3 is a sectional view taken on line 3—3 of Fig. 2. Fig. 4 is a fragmentary view.

In the preferred embodiment of my in- 50 vention the same is preferably constructed of a sheet metal such for instance as galvanized iron, yet it is to be recognized that this may be varied in accordance with the existing conditions.

55 In reducing my invention to practice, I provide a suitable body portion 10, the re-

spective sides 11 thereof having their upper edges cut slanting as shown at 12 in order to support the fender structure at a desired angle, as will presently appear. The front 60 edge of the body portion is bent upwardly and curved as at 13 in order to provide a suitable supporting lip for the fender structure, and at the same time, materially add to the neatness and appearance of the device. 65 In order that the body portion may be quickly and easily manipulated, a handle member 14 is provided and secured to the front portion 13 by such means as shown at 15. 70

The rear end of the body portion is pro- 75 vided with inwardly projecting portions 16 which in the use of the device form suitable vertical shoulders which abut the walls of the fire place in an obvious manner, in order to limit the inward movement of the apparatus. From the respective inner ends of the members 16, project other side members 17 that are connected as at 18 to form a suit- 80 able restricted pan structure. This pan structure 19 serves as an ash pan, and is nor- mally arranged directly below the grate in order to catch the ashes directly ejected therefrom. It is obvious therefore that the ashes collected within the pan 19 may be de- 85 posited in the pan 10 and so collected until the interior structure is full. Further, a shaft 20 is journaled transversely of the pan 10 through the respective side portions 11 and may be secured in position by any suit- 90 able means. A fender structure is now pro- 95 vided that consists of a bottom portion 21 that carries spaced apart sleeves 22 for en- gagement with the shaft 20, to hold the fender in pivotal relation with the remain- ing structure. The bottom 21 is provided of a suitable width so that it projects over the upper edges of the side portions 11 and rests on the curved front portion 13 as shown. Suitable sides 23 and a front portion 100 24 are provided on the respective edges of the member 21 and project upwardly there- from as shown in order to form an auxiliary pan structure, to catch and collect live coals, sparks and other particles falling from the 105 unprotected side of the grate. It is readily apparent that the contents of the fender may be deposited in the pan 10 or by simply rock- ing the fender on the shaft 20 in an obvious manner in the pan 19.

In order to facilitate the removal and re- placement of the apparatus, a bail 25 is em-

ployed and connected to the sides 11 as shown, the same normally lying in the position shown in Fig. 3.

From the foregoing it will be recognized that my invention consists of but a few simple parts which can be stamped from sheet metal and easily and quickly bent into suitable form. Therefore it will be appreciated that the device can be manufactured at a 10 minimum cost.

In reducing my invention to practice I find that the form referred to herein as the most practical and preferred embodiment is the most efficient; but realizing that certain 15 conditions will necessarily vary in concurrence with the adoption of my device, I desire to emphasize the fact that various minor changes in details of construction and proportion of parts may be resorted to when 20 required, without sacrificing any of the advantages of my invention as defined in the appended claims.

Having thus fully described my invention, what I claim as new and desire to secure by Letters Patent is:

1. In a device of the character described; an ash pan having an extension portion for disposition beneath a grate, a cover movably associated with said ash pan, and 25 standing flanges carried by said cover; whereby said cover forms a collector.
2. In a device of the character described, an ash pan having an extension for disposition beneath a grate, a shaft mounted on 30 said ash pan at a point spaced from said

extension, and a fender member movably mounted on said shaft, and said fender member provided with upstanding flanges; whereby said fender member forms a collector to deliver to said ash pan upon tilting. 40

3. In a device of the character described, an ash pan having an extension for disposition beneath a grate, a fender member, means pivotally connecting said fender member and said ash pan at a point spaced 45 from said extension, said ash pan having the upper edges of its side members cut slanting toward its outer end, said fender member adapted to normally lie on said slanting edges, upstanding side and end 50 flanges on said fender member providing a collector, and said fender member adapted to deliver ashes to said ash pan upon tilting.

4. In a device of the character described, a pan structure having an extension for disposition beneath the grate, a shaft mounted on said pan structure at a point spaced from said extension, a fender mounted on said shaft, said fender normally engaging the upper edges of said pan structure and adapted 55 to deliver ashes to said pan structure upon tilting, a handle on said pan structure, and a bail for manipulating said pan structure, substantially as described.

In testimony whereof I affix my signature 60 in presence of two witnesses.

MRS. ETHEL M. RYAN.
